SLICING MACHINE

Arthur A. Kottmann, Davenport, Iowa, assignor,
by mesne assignments, to The Bettendorf Company, a corporation of Maryland

Application December 20, 1940, Serial No. 370,958

13 Claims. (Cl. 146—83)

This invention relates to band blade slicing machines, and more particularly to an improved means for mounting a drum for supporting the endless cutter bands.

It is an object of the invention to provide a generally improved support for a slicing machine band drum which permits the drum to be shifted laterally, to thereby uniformly vary the tension of all of the cutter bands carried by the drum, in combination with means for shifting or adjusting one end only of the drum, so that the drum can be adjusted into parallelism with the other blade supporting means or drum of the machine.

Other objects relate to improvements in the drum structure which avoid the contamination of the cutter bands by lubricant from the drum journals; improvements in the drum mounting means which supports the drum at one end only so that cutter bands can be threaded into place over the other end, in combination with means for adjusting the drum laterally to position the same in parallelism with the other drum or blade supporting means of the machine; and improvements in the means for varying the relative positions of the drum supporting arms.

Another object is to provide a generally improved drum mount for a band type bread slicing machine which is simple in design and construction and relatively inexpensive to manufacture. Other objects and advantages will become apparent from the following detailed description of a suitable embodiment of the invention made in connection with the accompanying drawing, in which:

Figure 1 is a side elevational view, partly in section and with parts broken away or removed, showing a band blade slicing machine incorporating my improved drum support;

Fig. 2 is a sectional view taken on the line 2—2 of Fig. 1 and enlarged with respect thereto;

Fig. 3 is a fragmentary detail view taken approximately on the line indicated at 3—3 of Fig. 1 and enlarged with respect thereto; and

Fig. 4 is a fragmentary detail showing the adjustable arm of the drum support.

Referring to the drawing by numerals of reference which indicate like parts throughout the several views, the present invention is illustrated in connection with a slicing machine having a supporting structure which includes side frames 1 and 2, an infeed conveyor indicated generally at 3, and a discharge conveyor indicated generally at 4. Structural details of the machine that are not fully set forth or claimed herein form the

subject matter of my co-pending application, Serial No. 400,269 filed June 28, 1941.

Mounted on the supporting structure of the machine are spaced blade drums 5 and 6, the latter being supported in conventional manner and provided with a pulley or a sheave 7, over which is trained a belt or chain 8 driven by a motor 9. Endless cutter bands 10 are trained around the drums 5 and 6 and the runs of the cutters may be disposed in crossed relation so that the bands are in figure eight form. The specific arrangement of the cutter bands may be changed since the present invention is directed primarily to the support means for the drum 5. This support comprises a pair of spaced members or arms 11 and 12 which are mounted on a transverse support member or shaft 15 journaled or otherwise rotatably mounted in the frame members 1 and 2. The first arm 11 is rigidly or non-rotatably secured on the shaft or support member 15 adjacent the frame 2 as by means of a key 16, while the second arm 12 is loosely or, rotatably mounted on the shaft or support 15 adjacent the frame 1 and between the latter and a supplemental arm 17.

The supplemental arm or element 17 is rigidly or nonrotatably secured on the shaft or support 15, as by a key 18, and serves to prevent endwise or axial movement of the arm 12. Spaced flanges or abutment portions 19 and 20 of the second arm 12 provide therebetween a space 21 which receives the arm 17. Screws 22 are threaded through the side portions 19 and 20 in opposed relation to one another and engage opposite sides of the supplemental arm or element 17. In this manner the second arm 12 is locked or fixed in a definite rotative position relative to the shaft or support 15 and the first arm 11. By loosening one of the screws 22 while tightening the other, limited rotative movement can be imparted to the second arm 12 relative to the shaft 15 and the first arm 11.

The drum 5 is formed of a tubular member having a cylindrical outer surface for supporting the band blades or cutters. End members 23 are formed or provided interiorly of the drum 5 and are spaced inwardly toward one another from ends 24 of the tubular drum. A shaft 25 extends through the drum and has reduced diameter ends which receive bearing assemblies 26 mounted in the end members 23 of the drum structure. Covers 27 are secured to the end members 23, as by bolts 28, and have portions 29 which extend axially through the open ends of the drum 5.

Radially directed circumferentially extending flanges 30, formed on the margins of the portions 29, overlie the ends 24 of the drums and are spaced from the latter by annular slots or grooves 31. The drum member 5 with the ends 23 and the covers 27 form annular chambers 32 which open solely through the circumferential slots or grooves 31. By this arrangement lubricant from the bearings 26 is prevented from reaching the outer surface of the drum 5 and contamination of the cutter bands and the bread or other food product being sliced by the machine is avoided. Lubricant escaping from one of the bearings 26 moves along the shaft 25 to the exterior of the cover 27 and is thrown radially from the cover flange 30 by centrifugal force. Such grease or lubricant normally would not traverse the circumferential slot or groove 31.

The free end of the first arm 11 is formed with a journal or bore 33 which receives a stub shaft or spindle 34 supported thereby in approximately parallel relation to the support member or shaft 15. A set screw 35 or the like threaded through the end of the arm 11 engages the shaft or spindle 34 to secure the latter in place. A reduced diameter end 36 on the spindle 34 is received in an axial end opening or aperture 37 of the shaft 25 to support the latter in cantilever fashion from the first arm 11. The shaft 25 is secured on the spindle 34 by means of a ball 40 disposed in a radical pocket in the spindle 34 and engageable in a mating recess 41 formed in the wall of the axial recess 37. An elongated rod 42 is slidingly received within an axial bore extending through the spindle 34 and is formed with a reduced diameter portion 43 guided in the end of the spindle and providing a circumferential shoulder 44 which engages the ball 40 to force the latter into the recess 41, thereby locking the parts together and drawing end 45 of the reduced diameter portion of the shaft 25 against the shoulder formed on the spindle 34 by the reduced diameter end portion of the latter. The rod 42 is formed with a square end 46 which projects through the end of the spindle 34 so that the rod can be advanced or retracted by means of the threaded connection portion thereof indicated at 47.

The end of the second arm 12 is formed with a bore 48 that receives a threaded spindle 49 for longitudinal sliding movement, the spindle being supported by the arm 12 in parallel relation to the axis of the support shaft 15. Threads 50 on the spindle 49 engages a threaded collar 51 secured to the end of the arm 12 by means of screws 52. Thus, the spindle 49 may be advanced or retracted relative to the end of the arm 12, a square end 53 being provided on the end of the spindle to receive a suitable wrench or crank. The spindle 49 has a reduced diameter end portion 54 which extends toward the spindle 34, previously mentioned, and is normally in axial alignment with the latter. By means of the threads 50 the spindle 49 may be advanced so that the reduced diameter end 54 thereof is projected into an axial recess or socket 55 formed in one of the reduced diameter ends of the shaft 25. During normal operation of the slicing machine the end 54 of the spindle 49 is disposed within the recess 55 and the shaft 25 to assist or cooperate with the spindle 34 in supporting the drum. In removing or replacing cutter bands on the machine the bands are passed over the end of the drum normally supported by the spindle 49, the latter being sufficiently withdrawn from the socket 55

of the shaft 25 to permit the cutters to pass over the unsupported end of the drum 5.

Secured on the support shaft 15, preferably at the center thereof, and held against rotation relative to the shaft by means of keys 56 is a lever arm or member 57 located wholly outside of the path of the cutter bands 10 and disposed at an angle such as 90° to the normal positions of the arms 11 and 12. End 58 of the arm 57 bears against the end of an adjustable screw 59 threaded through a cross member 60 which extends between the side frames 1 and 2, being bolted to the latter as indicated at 61. Preferably, the cross frame member 60 is formed with lateral extensions 62 which straddle the arm 57 and have end portions 63 that embrace or engage the support shaft 15 to prevent deflection of the latter under the large forces to which it is subjected.

By rotating the screw 59, the lever arm 57 may be moved to pivot the support shaft 15 in the frame members 1 and 2 and thereby impart limited rotative movement to the arms 11 and 12 so as to swing the arms of the drum 5 carried thereby through an arcuate path. As shown in Fig. 2, the side frames may be provided with openings indicated at 64 which accommodate the ends of the arms 11 and 12, so that the rod 42 and the spindle 49 can be actuated in all positions of adjustment of the screw 59. Movement of the screw 59 in one direction swings the drum 5 away from the drum 6, thereby tensioning or increasing the tension simultaneously in all of the cutter bands 10. Conversely, movement or adjustment of the screw 59 in a reverse direction swings the drum 5 toward the drum 6 to simultaneously decrease the tension in all of the cutter bands. Preferably, a lock nut 65 is provided for the adjusting screw 59 to hold the latter in fixed or adjusted position.

During normal operation of the machine the axis of the drum 5 should be maintained in parallelism to the axis of the drum 6. If the ends of the drums adjacent one side frame of the machine should become closer together than the ends adjacent the other side frame of the machine, the endless cutter bands would tend to migrate or move toward the drum ends closest together. This migration of the blades would tend to occur even though the drum axes are out of parallel only a few thousandths of an inch. By means of the screws 22 carried by the second arm 12, the left end of the drum as viewed in Fig. 2 can be shifted toward or away from the corresponding end of the drum 6. In this manner the relative positions of the axes of the blade supporting drums can be adjusted, thereby equalizing or adjusting the tension in the cutter bands.

The present invention thus provides in combination means including the single lever arm 57 for simultaneously and uniformly adjusting the tension in all of the cutters, with means comprising the supplemental arm 17 for shifting one end of one of the drums toward and away from the corresponding end of the other drum to thereby equalize the tension in all of the cutter bands. Furthermore, the invention provides in combination with the blade tension equalizing and adjusting means above mentioned, means comprising the retractable spindle 49, permitting blades to be removed or replaced on the adjustable drum without removing the same from the machine and while the drum is supported cantilever fashion by the pivoted arm 11.

The principles of the present invention may be utilized in various ways, numerous modifications

and alterations being contemplated, substitution of parts and changes in construction being resorted to, as desired, it being understood that the embodiments shown in the drawing and described above are given merely for purposes of explanation and illustration without intending to limit the scope of the claims to the specific details disclosed.

What I claim is:

1. In a band blade slicing machine having a supporting structure, a drum, shaft means for rotatably mounting the drum, a pair of spaced arms pivotally supported on the structure and engaging the shaft means at opposite ends of the drum, means for moving the arms in unison to shift the drum laterally, and means providing limited pivotal adjustment of one arm relative to the other arm.

2. In a band blade slicing machine having a supporting structure, a drum, shaft means for rotatably mounting the drum, a pair of spaced arms and means supporting the same on the structure for coaxial pivotal movement, said arms having engagement with the shaft means at opposite ends of the drum, means for pivotally moving the arms in unison to shift the drum laterally, and means providing limited pivotal adjustment of one arm relative to the other arm about the pivot axis of the arms.

3. In a band blade slicing machine having a supporting structure, a drum, shaft means for rotatably mounting the drum, a support member mounted on the structure for limited rotative movement, a pair of arms mounted on said member and engaging the shaft means at opposite ends of the drum, means for imparting rotative movement to the support member to swing the arms in unison, and means providing limited pivotal adjustment of one arm relative to the other arm on said support member.

4. In a band blade slicing machine having a supporting structure, a drum, shaft means for rotatably mounting the drum, a support member mounted on the structure for limited rotative movement, a pair of arms mounted on said member, one arm engaging the shaft means at one end of the drum and adapted to support the same cantilever fashion and the other arm having movable means adapted to engage the shaft means at the other end of the drum, and means for imparting rotative movement to the support member to swing the arms in unison.

5. In a band blade slicing machine having a supporting structure, a drum, shaft means for rotatably mounting the drum, a support member mounted on the structure for limited rotative movement, a pair of arms mounted on said member, one arm engaging the shaft means at one end of the drum and adapted to support the same cantilever fashion and the other arm having movable means adapted to engage the shaft means at the other end of the drum, means for imparting rotative movement to the support member to swing the arms in unison, and means providing limited pivotal adjustment of one arm relative to the other arm on said support member.

6. In a band blade slicing machine having a supporting structure, a drum, a support member mounted on the structure for limited rotative movement, a pair of arms mounted on said member for movement in unison therewith, means connecting the arms and the drum in opposite ends of the latter to rotatably support the same, and means providing limited pivotal adjustment

of one arm relative to the other arm on said support member.

7. In a band blade slicing machine having a supporting structure, a member mounted on the structure for rotative movement, a first arm rigidly mounted on said member, a second arm rotatably mounted on said member in spaced relation to said first arm, a drum and means rotatably mounting the same between the ends of said arms, adjustable means connecting the second arm and the member to hold such arm in various rotative positions relative to the member, and means for imparting rotative movement to the member to swing the arms in unison and thereby shift the drum laterally.

8. In a band blade slicing machine having a supporting structure and a pair of drums for mounting a plurality of endless band cutters in side by side relation, means for rotatably mounting one of the drums on the structure comprising a pair of spaced arms having engagement with said one drum at opposite ends of the latter, a transverse support pivotally mounted in the structure and having the arms mounted thereon for pivotal movement therewith, means for imparting relative rotative movement of one arm on said support relative to the other arm to shift one end of the said one drum toward and away from the other drum, and means for imparting limited rotative movement to the support to shift said one drum laterally toward and away from the other drum while maintaining the drum axis in parallelism.

9. In a band blade slicing machine having a supporting structure including side frames, a transverse support extending between the side frames and rotatably mounted thereby, a pair of spaced arms on the support means for adjusting the relative rotative positions of the arms on the support, means for imparting limited rotative movement to the support to swing the arms in unison, and a drum and means for rotatably mounting the same between the ends of the arms.

10. In a band blade slicing machine having a supporting structure, a support rotatably mounted on the structure, a drum carrying arm rotatably mounted on the support to turn about the rotational axis of the support, a supplemental arm secured on the support for rotation therewith, an adjustable means connecting said drum carrying arm and the supplemental arm to provide for rotative movement of the drum carrying arm in unison with the support and whereby the rotative position of the drum carrying arm relative to the support can be varied.

11. In a band blade slicing machine having a pivoted support member and a drum carrying arm mounted to turn on said member, an adjustable connection between the member and the arm comprising a supplemental arm rigidly secured to the support, and screw means connecting the drum carrying arm and the supplemental arm for shifting the arms relative to one another about the pivotal axis of the support member.

12. In a band blade slicing machine, a supporting structure including spaced frame members, a support rotatably carried by said members, a pair of arms mounted on the support in spaced relation, a drum rotatably supported between the ends of the arms, means for imparting rotative movement to the support to swing the arms over arcuate paths and thereby shift the drum laterally, the mounting for one of the arms

on the shaft including an element rigidly attached to the support, and a pair of opposed screws carried by the arm and engageable with said element to adjust the relative rotative position of such arm on the support.

13. In a band blade slicing machine having spaced frame members, a support shaft journaled in the members, a first arm rigidly secured on the shaft adjacent one frame member, a second arm mounted on the shaft for rotative movement adjacent the other frame member, a supplemental arm rigidly mounted on the shaft adjacent the second arm, adjustable means con-

necting the second arm and the supplemental arm so that the second arm rotates in unison with the first arm, a blade supporting drum, a shaft extending through the drum and supportable by the first arm in cantilever fashion for threading band blades onto the drum, a spindle carried by the second arm and engageable with the free end of the shaft to support the same during operation of the machine, and means for 5 rotating the support shaft to swing the arms in 10 unison and thereby shift the drum laterally.

ARTHUR A. KOTTMANN.
